MAGNETIC RECORD MEMBER

Herbert Wagner and Erich Merkel, both of Ludwigshafen (Rhine), Germany, assignors to Badische Anilin- & Soda-Fabrik Aktiengesellschaft, Ludwigshafen (Rhine), Germany

Filed Nov. 14, 1961, Ser. No. 152,173

Claims priority, application Germany Nov. 16, 1960

6 Claims. (Cl. 117—72)

This invention relates to a magnetic record member comprising a tape as base or carrier and one or more layers applied thereto of a magnetizable substance incorporated in a binder. More particularly, the invention relates to a special binder adapted for use in making magnetic record members.

The active layer of magnetic record members, which consists of magnetizable substances finely dispersed in a binder, is in very close contact, during sound recording and reproduction, with the magnetic heads of the recording apparatus. For this reason, the active layer is subjected to heavy abrasion so that, after frequent sliding of the layer past the magnetic heads, the magnetic record member may become completely unfit for use and the narrow gap between the magnetic heads is fouled by the abraded particles. To avoid these disadvantages, the binder should have maximum resistance to abrasion.

Binders which have hitherto been used in the manufacture of magnetic record members are polyvinyl chloride, vinyl chloride copolymers, polyacrylates, polycarbonates, polyurethanes, and varnishes based on epoxy resins. The said binders, however, have various disadvantages. Thus, active layers comprising polyvinyl chloride or vinyl chloride copolymers as binder show heavy abrasion, especially when they are subjected to high stresses, such as are encountered, for example, in apparatus for recording television impulses. When polycarbonate resins are used, considerable difficulties arise in coating the carrier tape because of the long drying periods or reaction periods required.

We have found that the said disadvantages are obviated by using as binder, in at least one layer applied to a plastic carrier tape and containing a magnetizable substance, a copolymer of 60 to 90% by weight, preferably 70 to 80% by weight, of styrene and 40 to 10% by weight, preferably 30 to 20% by weight, of acrylonitrile.

The copolymer used as binder should have a K-value of 60 to 80, advantageously of 68 to 75.

The ratio of binder to magnetizable substance is advantageously from 1:2 to 1:7.

As compared with the prior art binders, the binder according to this invention is distinguished by several advantages. In particular, it has extremely high resistance to abrasion, which can be determined by the following method: A magnetic record member having the form of a tape and a certain degree of magnetization is run, at a certain contact pressure, past a surface 3 meters in length which has been roughened to a certain degree. The decrease in thickness of the active layer is then determined by electroacoustic measurement of the decrease in sensitivity.

The abrasion values for known binders and the abrasion value for the binder according to this invention are given in the following table. The various tests were carried

2

out under the same conditions so that the results could be compared.

TABLE

	Binder used	Abrasion (microns)
5	Copolymer of vinyl chloride and vinyl acetate (1:1); K-value 58	2.6
10	Copolymer of ethyl methacrylate and ethyl acrylate (1:1); K-value 60	1.8
15	10 Binder according to this invention; K-value 73	1.0

Although the binder according to this invention has a much higher abrasion resistance than the known binders, magnetic record members coated with this binder are surprisingly far less abrasive to the magnetic heads of recording apparatus.

The results of three successive measurements of the abrasive action of magnetic record members coated with the binder according to this invention and with a copolymer of vinyl chloride and vinyl acetate, respectively, are given in the following table. The measurements are carried out as follows: A magnetic record member 1000 meters in length is run past a rod of tin solder at a contact pressure of 2500 g./cm.². The rod is weighed before and after the test, the difference in weight being a measure of the abrasion.

TABLE

30	Measurement No.	Abrasion of rod (mg./1,000 meters of tape)		
		I	II	III
35	Binder used:			
	Binder according to this invention (78% styrene and 22% acrylonitrile); K-value 73	4.5	3.1	1.9
	Copolymer of vinyl chloride and vinyl acetate (1:1); K-value 58	15.6	8.5	7.8

40 A further advantage of the binder according to this invention over the prior art binders is to be seen in its better compatibility toward iron oxide pigments. The magnetizable pigments can be packed more closely in the new binder and are therefore also present in greater density in the dried layer. This results in increased magnetic sensitivity of magnetic record members provided with such a layer. The following table shows the obtainable pigment densities and the sensitivities of magnetic record members provided with an active layer comprising, respectively, the binder according to this invention and a prior art binder consisting of a copolymer of vinyl chloride and vinyl acetate.

TABLE

	Binder used	Pigment density (g./cm. ³)	Sensitivity (db)
55	Binder according to this invention (78% styrene and 22% acrylonitrile); K-value 73	1.59	+2.6
60	Copolymer of vinyl chloride and vinyl acetate (1:1); K-value 58	1.20	-0.2

65 The sensitivity is given with reference to a comparison tape according to DIN (German Industrial Standard) 45, 513.
